UNITED STATES PATENT OFFICE.

FRED FRAZER, OF SYRACUSE, NEW YORK.

DESIGN FOR A HAME-TOP.

SPECIFICATION forming part of Design No. 23,147, dated March 20, 1894.

Application filed January 24, 1894. Serial No. 497,939. Term of patent 14 years.

To all whom it may concern:

Be it known that I, FRED FRAZER, a citizen of the United States, residing at Syracuse, county of Onondaga, and State of New York, have invented and produced a new and original Design for Hame-Tops, of which the following is a specification, reference being had to the accompanying drawings, in which I show a side elevation thereof.

Figure 1, shows a side view of the design, complete. Fig. 2, shows a cross section on line $-x-x-$, Fig. 1.

The leading feature of my design consists in the representation of the head of a horse with a recess in the lower end of the bust, substantially as shown.

—*a*— represents the head, —*b*— the neck and —*c*— a portion of the body upon which it is mounted, —*d*— representing a collar and —*e*— a bridle.

20

Having described my invention, what I claim is—

The design for a hame top, substantially as herein described and shown.

In witness whereof I have hereunto set my hand this 11th day of January, 1894.

FRED FRAZER.

In presence of—
HOWARD P. DENISON,
M. M. BORST.
